UNITED STATES PATENT OFFICE.

CARL SCHWARTZ, OF SHEBOYGAN FALLS, WISCONSIN.

PHONOGRAPH MOTOR.

Application filed June 16, 1924. Serial No. 720,311.

To all whom it may concern:

Be it known that I, CARL SCHWARTZ, a citizen of the United States, and resident of Sheboygan Falls, in the county of Sheboygan and State of Wisconsin, have invented certain new and useful Improvements in Phonograph Motors; and I do hereby declare that the following is a full, clear, and exact description thereof.

10 This invention relates to phonograph motors.

Objects of this invention are to provide a phonograph motor which is equipped with governing mechanism, which may be adjusted while the motor is running, and in which a micrometer adjustment of governing mechanism may be most readily attained.

Further objects are to provide an electric phonograph motor in which a very simple type of micrometer adjustment for the governor is secured, in which any one of a multitude of different speeds may be secured with the utmost precision, and in which the control for the governor may be located in an easily accessible position.

Further objects are to provide a compact electric phonograph motor and governing mechanism which is of simple construction, and which may be cheaply produced.

30 An embodiment of the invention is shown in the accompanying drawings, in which:—

Figure 1 is a vertical fragmentary sectional view through a phonograph equipped with the motor and governor mechanism, such view corresponding to the line 1—1 of Figure 2.

Figure 2 is a bottom view of the structure shown in Figure 1.

Figure 3 is a transverse sectional view on the line 3—3 of Figure 1.

Figure 4 is a transverse sectional view on the line 4—4 of Figure 1.

Figure 5 is a view taken at right angles to Figure 4 showing the governor mechanism in its position for greatest speed.

Figure 6 is a view corresponding to Figure 5 showing the governor mechanism in a different position of adjustment.

50 The phonograph motor comprises a unit carried by a base plate 1 supported from an attaching plate 2 (see Fig. 1) and held resiliently from said plate by means of

springs 3 and 4 positioned on opposite sides of the bed plate 1, and carried by bolts 5 hung from and secured to the attaching plate 2. This attaching plate is secured to the lower side of the phonograph cabinet top 6 and the bolts 5 are preferably provided with tapered heads set in recessed apertures formed in the attaching plate 2 so as to be securely locked in place when the attaching plate is secured to the top 6. This bed plate is provided with downwardly extending projections 7 or standards which carry the bearings 8. These projections are preferably provided with oil receiving apertures 9 for supplying the bearings, a suitable aperture and suitable absorbent material being employed, as shown in Figure 1, with reference to the bearing. It is preferable to make these spherical and to correspondingly shape the supporting portions, as shown in such figure, so as to secure automatic alignment thereof.

An electric motor is carried by the bed plate 1, and is provided with a field 10 and an armature 11 and commutator 12, suitable brushes, of course, being employed as illustrated in Figure 2. It is preferable to connect the field and armature in series, as shown in Figure 2, and it is preferable to lead the terminals to binding posts 13 carried by an insulating block 14, such insulating block being conveniently secured to a portion of the housing 15 for certain parts of the mechanism hereinafter described. The motor is provided with a driving shaft 16 and carries a worm 17, such worm being located within the housing 15, as may be seen from Figure 1. This worm meshes with a worm wheel 18 rigidly secured to the record rotating spindle 19, such spindle projecting through suitable bearings carried by the bed plate 1 and also projecting upwardly through the phonograph top.

A drum 20 is rigidly attached to the outer end of the motor driving shaft 16, as shown in Figure 1, and is closely surrounded by a cylindrical housing 21, as may be most clearly seen from Figures 1 and 4. This housing 21 is provided with ears 22 which are apertured and which, together with the bed plate 1, receives dowel pins 23 to secure accurate positioning of such housing, suitable screws 24 being employed to secure the

housing in its fixed relation to the bed plate. This drum 20 provides a fly wheel effect for the motor in addition to the mass of the armature and thus prevents any temporary small variation in speed even when the stylus of the reproducer is loaded excessively at certain portions of the record. However, a governor is provided for the motor and is preferably carried by the drum 20.

10 The governor mechanism comprises a plunger 25 which is provided with a friction face 26 of any suitable material which may either contact with or be held out of engagement with the inner peripheral portion of the casing 21. This plunger is supported by means of a tightly wound helical spring 27 secured at its inner side to the plunger supporting member 28, such member also including a plate 29 provided with an aperture 30 equipped with inwardly converging or slanting walls and with a cylindrical portion, as may be clearly seen from Figures 4, 5 and 6. The plunger 25 and the plunger supporting portion are slidably carried within a diametrically arranged aperture 31 which passes through the drum 20. This aperture may be formed by boring a hole along a diameter and through the drum 20, as shown in Figures 1 to 6. If desired, a closing member 32 may be provided for one end of the aperture.

15 The casing is provided with an outwardly projecting apertured boss 33 accurately seated within a central cut out portion 34 in the casing and held thereto in any suitable manner. This boss carries a controlling and adjusting plug 35 for the governor mechanism. This plug is provided with a conical terminal 36 adapted to enter the aperture 30 and to thus adjust the position of the plunger 25 with reference to the inner peripheral portion of the casing 21. The plug is arranged in axial alignment with the motor driving shaft 16, as shown in Figure 5, and is preferably provided with a slot 37 adjacent its outer end. This slot receives the flange 38 of a screw 39 threaded into the boss 33, as shown in Figures 5 and 6. The screw is controlled by means of a flexible shaft 40 which passes to a manual adjusting thumb screw 41 (see Fig. 1) such adjusting screw being carried within a disk 42 and located upon the exterior or upper side of the phonograph top 6. If desired, this adjusting thumb screw may be threaded to the disk 42, as shown, and consequently the distance between such screw and the controlling screw 39 may be maintained constant if the threads are of the same pitch.

20 By rotating the thumb screw 41, the adjusting screw 39 is rotated and the plug 35 is moved to the desired point thus providing a micrometer adjustment for the plunger 25 and thus controlling the speed of the apparatus.

It is to be noted that the centrifugal force tends to draw the plunger out into engagement with the inner portion of the casing 21, and that the exact setting of the support 28 for the plunger may be controlled by the 70 micrometer adjustment.

It is to be noted that the motor is a series motor and is adapted to run upon either alternating or direct current and may be connected with ordinary lighting supply mains. 75

Further, this series motor is not a constant speed motor due to the well known characteristics of the series motor, and constantly cooperates with the utmost facility with the governing mechanism, the speed of the motor being accurately controlled by the mechanical governor. 80

Although the invention has been described in considerable detail, it is to be understood that the invention may be variously embodied and is, therefore, to be limited only as claimed. 85

I claim:

1. In a phonograph, the combination of a motor having a driving shaft, a record rotating spindle operatively connected thereto, a guide carried by said driving shaft, a plunger slidably carried thereby and mounted eccentrically relatively to said driving shaft, a plunger supporting member, a spring joining said plunger supporting member and said plunger, a cam member mounted coaxially with said shaft and cooperating with said plunger supporting member for controlling the position of said plunger, 90 means for controlling said cam member, and a circular casing coaxial with said shaft, and enclosing said plunger, said plunger being adapted to frictionally slide along said casing under certain conditions of adjustment 100 of said cam member.

2. In a phonograph, the combination of an electric motor having a driving shaft, a record rotating spindle connected thereto by speed reduction mechanism, a drum carried by said driving shaft and having a diametrical passage thereacross, a circular casing surrounding said drum, a plunger slidably mounted in said passage and adapted to frictionally engage the interior periphery of said casing, a supporting member slidably carried by said drum, a spring connecting said supporting member and said plunger, a conical plug engaging said supporting member and mounted in axial alignment with said driving shaft, and micrometer means for adjusting said plunger. 110

3. In a phonograph, the combination of a series electric motor having a driving shaft, a record rotating drum connected thereto by speed reduction mechanism, a drum carried by said driving shaft and having a transversely extending aperture, a circular casing surrounding said drum, a plunger slidably mounted within said aperture and ec- 125 130

centric with reference to said drum, a supporting member for said plunger carried by said drum and having an aperture therein, a spring connecting said supporting member and said plunger, a conical plug mounted in axial alignment with said driving shaft and adapted to enter the aperture in said

supporting member, and micrometer means for adjusting the position of said plug.

In testimony that I claim the foregoing I ¹⁰ have hereunto set my hand at Sheboygan Falls, in the county of Sheboygan and State of Wisconsin.

CARL SCHWARTZ.
